UNITED STATES PATENT OFFICE.

WILLIAM A. GOLLNAST, OF VALLEJO, CALIFORNIA.

HOIST.

Application filed June 29, 1921. Serial No. 481,250.

To all whom it may concern:

Be it known that I, WILLIAM A. GOLLNAST, a citizen of the United States, residing at Vallejo, in the county of Solano and State 5 of California, have invented new and useful Improvements in Hoists, of which the following is a specification.

This invention relates to a hoist, and particularly pertains to a safety device therefor. 10 Heretofore numerous accidents have occurred in the operation of heavy hoists, such as lock cranes, due to the fact that the boom hoist shaft was not positively engaged and thus allowed the crane to fall with its burden.

15 It is a principal object of the present invention to provide automatic and positively operating means whereby the disengagement of the hoist shaft from the main drive shaft will be accompanied by a positive locking of 20 the boom hoist shaft.

The present invention contemplates the use of jaw clutches to operatively establish driving connection between the main drive shaft and the boom hoist shaft, and which 25 clutches are actuated by means controlling a lock device acting upon the boom hoist shaft to prevent counter-rotation thereof. The invention is illustrated by way of example in the accompanying drawings in 30 which

35 Fig. 1 is an enlarged fragmentary view in elevation showing the safety mechanism with which the present invention is concerned, and particularly disclosing the lock pawl as in its operative position;

Fig. 2 is a fragmentary view in plan showing the parts disclosed in Fig. 1;

Fig. 3 is a view similar to that shown in Fig. 1 illustrating the inoperative position 40 of the lock pawl;

Fig. 4 is a view similar to Fig. 3 showing the automatic safety action of the lock pawl when the jaw clutches are not positively engaged.

45 In referring to the drawings it will be understood that only the parts of a boom hoist mechanism are shown with which the present invention is concerned, and that the general construction and arrangement of the 50 hoist is non-essential to the safety device here disclosed, this device being applicable to numerous hoist and driving mechanisms.

55 Broadly considered, the invention is concerned with a main drive shaft 10 acting through gears 11 and 12 to drive a boom hoist shaft 13. As shown in the drawings,

these shafts are disposed at right angles to each other. The gear 11 is fitted with a hub 14 carrying clutch jaws 15. These jaws are adapted to be engaged by jaws 16 of a 60 sliding clutch member 17. The clutch member is splined onto the shaft 10 by a key 18. The hub of the sliding clutch 17 is formed with an annular groove carrying pins 19 of a shifting yoke 20. The shifting yoke is 65 mounted on a fulcrum pin 21 supported from a fixed lug 22 forming a part of the main frame of the structure. Formed integral with the shifting yoke 20 is a safety finger 23. This finger is adapted to oscillate simultaneously with the yoke as actuated by a lever arm 24. An operating rod 25 is pivoted to the end of this lever arm, said rod being actuated by any suitable control mechanism. The safety finger 23 extends substantially 70 horizontally and is formed with a down-turned end 26. This member is adapted to actuate a safety pawl 27. This pawl is mounted upon a pin 28 carried by a pad 29 supported on one of the main frame members 80 of the hoist, as indicated at 30. This pawl is formed integral with a counterweight arm 31 which carries a weight 32 by which the pawl will normally be held out of engagement with the ratchet teeth of a locking disc 85 33. This disc, as shown in Figs. 1, 3 and 4, is formed with a plurality of equally spaced ratchet teeth arranged around the circumferential edge. The disc is keyed to the boom hoist shaft 13 and the teeth are so 90 formed as to prevent counter-rotation of this shaft when they are engaged by the pawl.

It often happens that the jaws of the clutch members 14 and 17 do not properly engage or dis-engage and that the pawl will only be in slight engagement with the teeth of the ratchet. In order to prevent this and insure a positive locking action on the part of the pawl, an emergency detent 33^a 100 is pivoted to the back of the pawl by a pin 34. This detent stands substantially parallel to a lug 35 projecting from the back of the pawl and which lug has an end face adapted to register with the end face of the 105 extension 26 when the members are as shown in Fig. 1. In the event, however, that the clutch jaws do not properly register, the pawl will be yieldably held by pressure of the safety finger extension 26 against the detent 33^a. This detent is fitted with a compression spring 36 passing around a bolt 110

37, which bolt tends to normally hold the detent against the lug 35, as shown in Figs. 1 and 3.

In the operation of the present invention, 5 the mechanism here disclosed may be installed as a part of a boom hoist equipment with the ratchet disc 32 fixed upon the boom hoist shaft and the jaw clutches mounted upon the main drive shaft. When it is intended to disconnect the two shafts, the bar 25 is drawn in the direction of the arrow *a*, as indicated in Fig. 3, thus pressing the end of the safety finger 23 down against the upper flat face of the detent 33^a. Simultaneously with this action, the shifting yoke 20 will swing in the direction of the arrow *b*, thus moving the clutch member 16 from engagement with the jaw 15. If the separation of the jaws is complete the downward action of the member 26 against the detent 33 will cause the pawl to swing in the direction of the arrow *c* until the flat face of the member 26 has cleared the face 38 of the detent, 20 after which pressure will be brought to bear against the upper flat face of the lug 35, thus tending to hold the pawl in positive engagement with a tooth of the disc, as indicated in Fig. 1 of the drawing. In the event, however, that complete disengagement of the clutch members is not effected, the boom shaft will still revolve and the pawl may be relieved by action of the detent 33^a. It will be evident that as the ratchet disc revolves it will tend to raise the pawl, 25 and with all of the parts rigid, some parts would undoubtedly be broken. However, due to the action of the detent, a raising action of the pawl will cause the detent to engage the side face of the member 26 and swing in the direction of the arrow *d*, as indicated in Fig. 4. This swinging action will be against the compression of the spring 36, thus insuring that when the tooth has cleared the end of the pawl the spring 35 will instantly force the pawl into the gullet of the tooth and cause the parts to assume the position indicated in Fig. 1. Analysis will also show that the detent will insure positive engagement of the teeth by the pawl, even though the clutches are actuated at an instant when the pawl and teeth 40 are not in direct engagement, the detent and its spring acting to force the pawl into engagement with the next registering teeth.

50 When it is desired to again engage the clutch members a counter-movement of the shifting yoke 20 will be accompanied by an upwardly swinging movement of the safety finger 23 to lift the pawl and release the clutch disc from its locking action.

60 It will thus be seen that the mechanism here provided insures positive and automatic cooperative action between the clutch of the drive shaft and the locking mechanism of a boom shaft whereby the release

of one of said members will cause actuation of the other, and vice versa, to positively insure that the dis-connection of the boom hoist from the main drive shaft will be accompanied by a locking action of this hoist 70 to continuously support the boom and thereby prevent accidents, all of which action is brought about by a comparatively simple and easily operated mechanism.

While I have shown the preferred form of 75 my invention, it is to be understood that various changes may be made by those skilled in the art without departing from the spirit of the invention.

Having thus described my invention, 80 what I claim and desire to secure by Letters Patent is:

1. In a device of the character described; a drive shaft; a freely rotating gear thereon; a driven shaft carrying a fixed gear in 85 constant mesh with said rotating gear; clutch means on the driving shaft for optionally engaging the freely rotating gear with said shaft; lock means on the driven shaft for preventing counter-motion of the driven 90 shaft; and means for simultaneously controlling the clutch mechanism and the lock means whereby disengagement of the clutches will cause operation of the lock means. 95

2. In a hoist mechanism, a main drive shaft, a boom hoist shaft adjacent thereto; constantly meshing gears carried by said shafts for imparting movement from the main drive shaft to the hoist shaft in a 100 given direction; clutch means carried by the main drive shaft for operatively connecting the drive shaft with its gears; a ratchet mechanism associated with the boom hoist shaft to prevent counter-rotation of 105 said shaft; and control means for simultaneously dis-engaging the clutches and engaging the ratchet mechanism.

3. In a hoist mechanism; a main drive shaft; a boom hoist shaft adjacent thereto; constantly meshing gears carried by said shafts for imparting movement from the main drive shaft to the hoist shaft in a 110 given direction; clutch means carried by the main drive shaft for operatively connecting it with its gear; a ratchet mechanism associated with the boom hoist shaft to prevent counter-rotation of said shaft; control means for simultaneously dis-engaging the clutches 115 and engaging the ratchet mechanism; and means for accommodating variation in the actuation of the clutches and registry of the ratchet and its pawl. 120

4. In a boom hoist; a drive shaft; a boom hoist shaft disposed at right angles thereto; a bevel gear keyed to the end of said boom hoist shaft; a complementary gear freely mounted upon the drive shaft and in constant mesh therewith; a clutch mechanism for operatively connecting the freely mount- 125 130

- ed gear to the main drive shaft; a ratchet disc upon the boom shaft; a pawl adapted to prevent counter-rotation of said disc; and means for simultaneously and alternately rendering the clutch and ratchet mechanisms operative.
5. In a boom hoist; a drive shaft; a boom hoist shaft disposed at right angles thereto; a bevel gear keyed to the end of said boom hoist shaft; a complementary gear freely mounted upon the drive shaft and in constant mesh therewith; a clutch mechanism for operatively connecting the freely mounted gear to the main drive shaft; a ratchet disc upon the boom shaft; a pawl adapted to prevent counter-rotation of said disc; means for simultaneously and alternately rendering the clutch and ratchet mechanisms operative; and means for causing the ratchet mechanism to become locked irrespective of the relative positions of the ratchet disc and the pawl at the time the clutch mechanism is actuated.
6. In a boom hoist; a drive shaft; a boom hoist shaft disposed at right angles thereto; a bevel gear keyed to the end of said boom hoist shaft; a complementary gear freely mounted upon the drive shaft and in constant mesh therewith; a clutch mechanism for operatively connecting the freely mounted gear to the main drive shaft; a ratchet disc upon the boom shaft; a pawl adapted to prevent counter-rotation of said disc; means for simultaneously and alternately rendering the clutch and ratchet mechanisms operative; and means for insuring that the pawl will positively engage the ratchet disc until the clutch members are absolutely in or out of engagement.
7. In a boom hoist mechanism; a main drive shaft; a bevel gear freely mounted thereon; a jaw clutch element carried by said gear; a jaw clutch element splined to the main drive shaft; a shifting yoke for moving said splined clutch member into and out of engagement with the first named clutch; a bevel gear in constant mesh with said freely mounted gear; a boom hoist shaft to which said gear is keyed; a ratchet disc fixed upon said shaft to prevent counter-rotation thereof; a pawl for engaging the teeth of said ratchet and normally held out of engagement therewith; and a lever simultaneously operated with the shifting yoke for alternately throwing the clutch members and the pawl and ratchet into and out of their engaged positions.
8. In a boom hoist mechanism; a main drive shaft; a bevel gear freely mounted thereon; a jaw clutch element carried by said gear; a jaw clutch element splined to the main drive shaft; a shifting yoke for moving said splined clutch member into and out of engagement with the first named clutch; a bevel gear in constant mesh with
- said freely mounted gear; a boom hoist shaft to which said gear is keyed; a ratchet disc fixed upon said shaft to prevent counter-rotation thereof; a pawl for engaging the teeth of said ratchet and normally held out of engagement therewith; a lever simultaneously operated with the shifting yoke for alternately throwing the clutch members and the pawl and ratchet into and out of their engaged positions; and a spring detent carried by the pawl for permitting yielding movement thereof when the clutches and ratchet mechanism do not happen to register in synchronism.
9. A hoisting and like apparatus including a drive shaft, a freely rotating gear thereon, a driven shaft, and fixed gear in constant mesh with said first named gear, clutch means on the driving shaft to engage the freely rotated gear, with its shaft, lock means on the driven shaft to prevent counter movement of the driven shaft when the clutch is disengaged, and means for simultaneously controlling the clutch, and the lock means, whereby disengagement of the clutches will cause operation of the lock means.
10. A hoisting and like apparatus comprising a drive shaft, a boom or like shaft adjacent thereto, constantly meshing gears upon said shafts to impart movement from the main drive shaft to the hoist shaft in either direction, clutch means upon the main shaft to operatively connect the drive shaft with its gears, a ratchet mechanism associated with the boom hoist shaft to prevent counter rotation of said shaft when the clutch is disengaged, and control means for simultaneously disengaging the clutches and engaging the ratchet mechanism.
11. A hoist and like mechanism comprising a main drive shaft, a boom hoist shaft, contiguous thereto, constantly meshing gears upon said shafts to impart movement from the main shaft to the hoist shaft in either direction, clutch means carried by the main drive shaft to operatively connect it with its gear, a ratchet mechanism upon the boom hoist shaft to prevent counter rotation of said shaft when the clutch is disengaged or imperfectly engaged, control means for simultaneously disengaging the clutches, and engaging the ratchet mechanism, and means to accommodate variation in the action of the clutches and registry of the ratchet and its pawl.
12. In a boom hoist and the like, a drive shaft and a boom hoist shaft disposed at right angles thereto, a bevel gear keyed to the boom hoist shaft, a complementary gear freely turnable on the drive shaft and in constant mesh with the first named gear, a clutch for operatively connecting the freely mounted gear to the main drive shaft, a ratchet disk upon the boom shaft, a pawl

to engage and prevent counter rotation of said disk, when the clutch is disengaged, or not perfectly engaged, means to simultaneously and alternately render the clutch and ratchet mechanisms operative, and means to lock the ratchet irrespective of the relative positions of the disk and pawl when the clutch is actuated.

13. In a boom hoist and like mechanism, a main drive shaft, a bevel gear freely mounted thereon, a jaw clutch element, carried by said gear, a jaw clutch element splined to the main drive shaft, a shifting yoke for moving said splined clutch member into and out of engagement with the first named clutch, a bevel gear, a boom hoist shaft to which said gear is keyed, and in constant mesh with the main shaft gear, a ratchet disk fixed to the boom hoist shaft, and a pawl to permit counter rotation thereof when the clutch is disengaged, or not properly engaged, said pawl being normally held out of engagement with the ratchet,

and a lever and shifting yoke to alternately throw the clutch members and the pawl and ratchet into and out of engagement.

14. In a hoist mechanism, a drive and boom hoist shafts with loose and fast intermeshing gears, a clutch and actuating bar, a ratchet fixed to the boom hoist shaft, a pawl engaging said ratchet, a lug projecting from the back of the pawl, and a finger movable with the clutch actuating bar, to be moved into contact with said lug.

15. In a hoist mechanism a drive shaft and a boom hoist shaft with loose and fixed intermeshing gears, a clutch and an actuating bar, a ratchet fixed to the boom hoist shaft, a pawl engageable with said ratchet, a lug upon the back of the pawl and a spring pressed detent pivoted therewith and a finger movable in unison with the actuating bar, to engage the detent and the lug on the pawl.

WILLIAM A. GOLLNAST.
